US00D415965S

United States Patent

[19]

Gerhart et al.**Patent Number: Des. 415,965****Date of Patent: ** Nov. 2, 1999****[54] BOTTLE WITH HANDLE**

[75] Inventors: **Mark Douglas Gerhart**, Westminster, Md.; **Harry Hamilton Haubert**, Sandy Hook, Conn.; **Zebulon Stevens Robbins, III**, Baltimore, Md.

[73] Assignee: **Lever Brothers Company**, New York, N.Y.

[**] Term: **14 Years**

[21] Appl. No.: **29/091,728**

[22] Filed: **Aug. 5, 1998**

[51] LOC (6) Cl. **09-01**

[52] U.S. Cl. **D9/531; D9/528**

[58] Field of Search D9/531, 528, 543; 215/396, 398, 383, 384, 385

*Primary Examiner—Lucy Lieberman**Attorney, Agent, or Firm—James J. Farrell***[57] CLAIM**

The ornamental design for a bottle with handle, as shown and described.

DESCRIPTION

FIG. 1 is a top, front and right side perspective view of a bottle with handle showing our new design.

FIG. 2 is a front elevation, the rear elevation is a mirror image thereto except for the conventional screw threading on the bottle neck.

FIG. 3 is a right side elevational view thereof.

FIG. 4 is a left side elevational view thereof.

FIG. 5 is a top plan view thereof; and,

FIG. 6 is a bottom plan view thereof.
